UNITED STATES PATENT OFFICE.

WILLIAM H. WADE, OF CHICAGO, ILLINOIS.

DEVICE FOR MARKING PHONOGRAPH RECORDS.

1,412,300.

Specification of Letters Patent. Patented Apr. 11, 1922.

Application filed July 1, 1921. Serial No. 481,763.

To all whom it may concern:

Be it known that I, WILLIAM H. WADE, a citizen of the United States, and a resident of Chicago, county of Cook, State of Illinois, have invented a certain new and useful Improvement in Devices for Marking Phonograph Records, of which the following is a specification.

This invention relates to the marking of phonograph records. These records are delivered to the retailer, of course, with the marks of the manufacturer thereon, but are ordinarily sold without anything to indicate the name or place of business of the retailer.

It has become, for various reasons, desirable to have the name and place of business of the retailer appear on the phonograph records permanently, so that not only will the retailer have the benefit of the advertising, but whereby certain things can be done which will help to safeguard the interests of the purchaser of the records. Preferably, phonograph records are marked on the face thereof, and inasmuch as these records usua-

lly have a round label pressed into the record at the center thereof, it is obvious that the most desirable place, for some purposes and for some reasons, to mark the records, is in the narrow space between said label and

the grooves of the record. In accordance with the invention, therefore, the device is provided with means for marking the record in this circular space, with the name of the retailer, or in any suitable or desired manner, but preferably in a way that makes the marking permanent or of such character that it cannot easily be erased. In addition, in view of the fact that this space is rather narrow, and because of the desirability of

accurately placing the marking in this space, the device is also provided with means for engaging the record to accurately position the latter relatively to the means which do the marking in said space. This may be done

in various ways, for example by providing the device with a projection which will enter the hole which is always formed in the center of the record, whereby the marking device will be centered by the same hole

which centers the record on the turntable of the phonograph. It is obvious, however, that the invention is not limited to any particular form or construction, and is not limited to the placing of the marking in any

particular position on the record. In some cases, or for some purposes, it may be pref-

erable to place the marking, for example, in the center of the space immediately outside of the grooves, near the edge of the record. In either case, however, regardless of whether the marking is placed on the inner circular space or the outer circular space on the record, it is preferable to employ means for positioning the marking device relatively to the record, either by engagement of something with the hole in the center of the record, or by engagement with something or some other portion of the record as may be desired. In the accompanying drawings, which are illustrative of one form of the invention,

Figure 1 is a top view of a marking device embodying the principles of the invention.

Figure 2 is a side elevation of said marking device showing it resting upon the phonograph record.

Figure 3 is an enlarged vertical section on line 3—3 in Figure 2.

Figure 4 is a plan view of the central portion of the record shown in Figure 3, illustrating the manner in which the marking device leaves its impression upon the narrow surface between the central label and the grooves of the record.

As thus illustrated, the marking device comprises a body portion 1, having a handle 2 of any suitable character on the back or top thereof. The face of said body 1 is provided with type 2, disposed in a circle, of any suitable character, such as rubber or metal or other material, this circle being of a diameter to properly locate the marking in said space 3 between the label 4 and the grooves 5 of the flat disc record 6, as shown more clearly in Figure 4, in a manner that will be readily understood. In order to properly locate the marking in this space, said device is preferably provided with any suitable or desired means for engaging the edges of the record, thereby to position the record and marking device relatively to each other. For example, the center of the body 1 can be provided with a cavity 7 containing a center post or pin 8 backed by a coil spring 9 which permits this pin or post to slide back into the said cavity when the marking device is pressed on an ink pad or on any other surface by which it is inked or supplied with the materials for producing the desired impression on the record. When the device is used, however, the post or pin 8 is placed in the center hole 10 of the record, thus center-

ing the device above the face or upper surface of the record. It is a matter of common knowledge, of course, that all disc records of this kind have a hole 10 for engaging the 5 turntable post of the phonograph. The pin 8 preferably accurately fits said hole and engages the opposite edges thereof, in order to accurately position the device. Thus, in accordance with the spirit and intention of the 10 invention, the hole 10 not only serves its original purpose of positioning the disc on the phonograph, but also serves the additional purpose of positioning the marking device on the disc itself. It will be under- 15 stood, however, as previously stated, that the positioning of the device over the face of the disc may be accomplished in any suitable or desired manner by means of any kind for engaging some portion or portions of the 20 edges of the disc, without departing from the spirit and intent of the invention.

As stated, the tool or marking device thus provided can be placed on an ink pad to ink the type 2, and when this is done the projection 8 will slide up into the body 1 to permit the desired inking operation. Of course, in order to carry out the intent and spirit of the invention, the ink or other liquid or substance or material for producing the impression 30 on the record should be of such character that it cannot be easily erased. There are known substances or inks or other things which can be used for this purpose and which in some cases will even eat into the substance 35 or material of the record itself, thus leaving the letters of the marking countersunk or characterized by a hollow effect on the face of the record. The label 4 is ordinarily pressed into the record, when the latter is 40 made, so that its outer surface is flush with the face or top surface of the record itself. When the name of the retailer is thus placed in the space 3 between said label and the grooves of the record, in such a way that the 45 name and the place of business of the retailer cannot be erased, it not only follows that the retailer obtains a certain kind of beneficial advertising, very obviously, but also that certain desirable results accrue in 50 the direction of the purchaser or user of the record, as will be readily understood by those familiar with the phonograph record business.

While the embodiment of the invention 55 shown and described involves the placing of the marking in the inner center of the circular space between the label and the grooves, it is obvious that the outer space between

the grooves and the outer edge of the disc can be utilized for this purpose, if so desired, 60 without departing from the spirit and intent of the invention. The disc has inner and outer edges, of course, and means are provided for engaging opposite edges to position the disc on the record. Moreover, the 65 marking thus placed on the disc can be of any suitable or desired character and may be the identification mark of the purchaser or user of the disc, so that discs when thus marked can be traced and recovered more 70 easily when stolen or lost.

Thus the invention provides a means for marking the record in a manner that protects the grooves against injury, during the 75 marking operation.

What I claim as my invention is:

1. Means for marking a phonograph record, comprising marking means disposed in position to mark the record in the annular 80 space ordinarily provided between the central label and the grooves of a disc record, and means for engaging the disc to position the latter and said marking means relatively to each other, thereby to ensure accurate placement of the marking in said annular 85 space.

2. Phonograph disc record marking means as specified in claim 1, comprising a handle for the back thereof, so that said means are in the form of a hand tool or device which 90 can be operated by one hand, and said positioning means comprising a projection in the center of the device for engagement with the hole ordinarily found in the center of any such disc record. 95

3. Phonograph disc record marking means as specified in claim 1, said positioning means comprising a provision for engagement with the hole ordinarily found in the center of any such disc record, means whereby said projection may slide into said device to permit the placing of the face of said device on an ink pad or other means for supplying the substance for marking the record, having a spring to keep said projection normally extended in position to engage said hole. 100

4. The combination of a phonograph disc record having record grooves and a smooth area, marking means disposed in position to operate upon the smooth area, means to engage the edges of the disc to position said marking means and prevent marking on said grooves, and means for operating said marking means. 110

WILLIAM H. WADE.
